SELF FILLING RESERVOIR DRAWING PEN

Filed March 20, 1929

Inventor:

Ellis Foulkes White

By his Attorney: Walter Guron.

UNITED STATES PATENT OFFICE

ELLIS FOULKES WHITE, OF COLWYN BAY, ENGLAND

SELF-FILLING RESERVOIR DRAWING PEN

Application filed March 20, 1929, Serial No. 348,605, and in Great Britain August 17, 1928.

This invention refers to self-filling reservoir drawing or ruling pens of the kind having means for varying the thickness of the line to be drawn, the invention being primarily intended for use by draftsmen, tracers, and the like, to save the time and effort now taken by the frequent re-filling of the ordinary ruling pen.

It is well known that the india ink used by draftsmen, etc., very quickly dries and congeals on the instruments, and it has hitherto been a great drawback in reservoir drawing pens that they do not permit a steady and continuous flow of ink.

The object of the invention is to provide an improved constructional form of pen of the type referred to, wherein the ink is caused to flow more readily and continuously from the container or reservoir into the nib, thus overcoming the before mentioned drawback. Other advantages will hereinafter appear.

According to the invention, the improved drawing pen comprises a hollow cylindrical body part, a hollow nipple secured to one end of the body part and carrying a compressible reservoir or container within the body part, means to fill and empty the reservoir, a cap or cover, and an adjustable, interchangeable metal nib secured to the nipple. Said nib has a hollow parallel-sided shank part with bifurcated end, which end is conical on its exterior and forms what are hereinafter called the "legs" of the pen. Secured within the hollow shank and extending both downwardly between the legs and upwardly into the reservoir is a feed wire, while screwing on to the shank and embracing the legs is a conical nut, with conical bore, by means of which the legs may be caused to approach each other to any desired degree within their normal limits.

Upon the accompanying drawing:—

Fig. 1 is an exterior view of the improved drawing pen, the cap being shown in dotted lines in its "closed" position.

Fig. 2 is a sectional elevation of one form of nib, and Figs. 3 and 4 are further sectional elevations, on planes at right angles to each other, of a modified form of the nib.

As shown, *a* is the hollow body of the pen

closed at one end, and screwed exteriorly at the other end. In the open end of the body *a* is secured a hollow nipple *b* which on its inner end carries a compressible container or reservoir (not shown). *c* is a pivoted lever for the filling and emptying of the reservoir in the known manner, and *d* is a cap adapted to screw on to the screwed end of the body *a*, or to fit the other and tapered end, the parts *a*, *b*, *c* and *d* in all material respects resembling a self-filling reservoir writing pen.

Fitting into the axial hole in the nipple *b* is one of a series of interchangeable nibs, the nibs being of different sizes to suit the taste of the user, or the nature of the work to be done. Each nib comprises a hollow parallel-sided shank *e*, bifurcated at one end to form two legs *f*, the ends of which are formed to a knife edge, and constitute the working edges of the pen. The shank *e* is screw-threaded on its exterior, to receive the screwed part of a conical nut *g*, a lock-nut *h*, and to screw into the nipple *b*, the lock-nut *h* being screwed against the end of the nipple to prevent the turning of the nib when the nut *g* is turned. The inner faces of the legs *f* are normally parallel, i. e., when the nut *g* is removed, but their outer faces taper towards each other from the shank to their working edges, so that on the nut *g* being screwed on to or off the shank the legs may be set at any required distance apart and within the limits of their springiness, and thus lines of different thicknesses may be drawn. The upper end of the nut *g* is flanged, and knurled to allow of the adjustments being made by the finger and thumb of the hand in which the pen is carried.

To prevent ink reaching the nut *g* and then getting on to the backs of the legs *f*, the latter are made to a width which is less than the smallest internal diameter of the nut, as clearly seen in Fig. 4. The nut bears only on the backs of the legs *f*.

The bore of the shank *e* is made to two diameters, and secured within the larger bore is a feed wire *i*, the wire being coiled at *j*, and retained in position by friction. The upper end of the wire extends within the con-

5 tainer, and the lower end extends to a point between the legs f about $\frac{1}{4}$ " from their ends. The lower end of the wire may be free as shown in Fig. 2, but is preferably secured to one of the legs as shown in Figs. 3 and 4. 10 Further, the wire may be of wavy form as in Fig. 2 or may be straight. The provision of the wire promotes and ensures a ready flow of ink into the nib of the pen, and being attached to the nib, it remains in position when the nib is removed for cleaning or other purposes.

15 The lock nut h may have a knurled edge or may be slotted so as to be manipulated by a key, and will preferably be of smaller diameter than the adjusting nut so as not normally to engage the fingers when the adjusting nut g is being moved.

20 What I claim is:—

20 1. In a self-filling reservoir drawing pen, an adjustable interchangeable metal nib comprising a parallel-sided shank, screw threaded for the whole of its length and having a central internal bore, a bifurcated extension on 25 one end of the shank shaped to form the legs of the pen, said legs tapering on their outer faces from the shank to their ends, a conical nut with conical bore screwing on to the shank and embracing the legs at its lower end only, a lock-nut on the shank and a feed wire secured within the bore of the shank and extending upwardly into the reservoir and downwardly between the legs to a point near their working edges, the legs of the pen being made to a width less than the smallest internal diameter of the conical nut, so that the nut bears only on the back of each leg, and the diameter of the nut at its lower end being only slightly greater than that of the 30 contiguous part of the nib, as set forth.

35 2. In a self-filling reservoir drawing pen according to claim 1, a shank having a central internal bore of two diameters and a feed wire secured by friction within the 40 larger bore of the shank, its upper end extending into the reservoir, and its lower end passing through the smaller bore and being secured to one of the legs of the pen, as set forth.

45 In testimony whereof I have signed my name to this specification.

ELLIS FOULKES WHITE.
